(57) **CLAIM**

The ornamental design for a therapy lamp, as shown and described.

DESCRIPTION

FIG. 1 is a rear, right and top perspective view of a therapy lamp, showing my new design;

FIG. 2 is a front left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area "9" in FIG. 1; and,

FIG. 10 is an enlarged view of area "10" in FIG. 2.

The dot-dash broken lines depict the boundaries of the enlarged views, and form no part of the claimed design.
